UNITED STATES PATENT OFFICE

117,288

DESIGN FOR A TILE

Eugene Parker, Los Angeles, Calif.

Application August 24, 1938, Serial No. 79,540

Term of patent 14 years

To all whom it may concern:

Be it known that I, Eugene Parker, a citizen of the United States, residing at 1525 North Formosa Avenue, Los Angeles, in the county of Los Angeles, State of California, have invented a new, original, and ornamental Design for Tile, of which the following is a specification, reference being had to the accompanying drawing, forming part thereof.

The figure is a perspective view of a tile showing my new design.

I claim:

The ornamental design for tile, substantially as shown.

EUGENE PARKER.
